ABSTRACT

A follow-hold circuit wherein the output follows the input until an external gating trigger disables the circuit whereupon the output remains at the last input level until the gating trigger enables the circuit again wherein the circuit comprises a differential feedback video amplifier and transistorized switch.

PULSE STRETCHER

GOVERNMENT INTEREST

The invention described herein may be manufactured and used by or for the Government of the United States of America for governmental purposes without the payment of any royalties thereon or therefor.

BACKGROUND OF THE INVENTION

Many times when working with narrow pulses it is desirable to "stretch" the width of the pulse. For instance a circuit that will follow and hold a narrow incoming pulse, i.e., 100 nanoseconds may be very useful when one is interrogating such narrow pulses. It is essential that any circuit that provides the "stretching" have a very fast rise and fall time and follow the incoming pulse amplitude very accurately.

BRIEF DESCRIPTION OF THE DRAWING

The drawing is a circuit diagram of the preferred embodiment of the invention.

DESCRIPTION OF THE PREFERRED EMBODIMENT

The circuit illustrated in the drawing utilizes a differential feedback video amplifier as a follow-hold amplifier. Transistors Q_1 , Q_2 and Q_3 represent the differential feedback video amplifier. Transistor Q_4 is a switch, normally on, that disables Q_1 , Q_2 and Q_3 when it is turned off.

Circuit operation is as follows. A narrow pulse, for instance 100 nanoseconds wide, is coupled in through coupling capacitor C_3 to the base of transistor Q_1 . Q_4 , the gating transistor, is biased on at this time, that is, it is in its normal condition. The capacitor, C_1 , is charged almost immediately to the input amplitude via the large gain of Q_1 and Q_3 . When the output amplitude equals the input amplitude, the closed loop gain equals 1 and the output is a faithful representation of the input amplitude. If Q_4 is disabled at this time, Q_1 , Q_2 , and Q_3 are turned off and C_1 will maintain the charge thereon. The only discharge path for C_1 at this time is through the high impedance of the back-biased junctions $V_{EB}(Q_2)$, $V_{EB}(Q_1)$, $V_{CB}(Q_3)$ and $V_{CB}(Q_4)$.

In order to terminate the output pulse, Q_4 is enabled by coupling another positive pulse through coupling capacitor C_2 to the base thereof and the charge on C_1 discharges through R_6 and Q_4 until $V_B(Q_2)=V_B(Q_1)$. If $V_B(Q_1)$ is zero, $V_B(Q_2)$ will also drop to zero.

If a high-impedance amplifier, for instance a field effect transistor source follower, is connected to the output, a narrow pulse can be stretched to several hundred microseconds.

A circuit analysis follows:

$$V_{c_1} = V_{cc} - \frac{I_t R_{c_1}}{2}$$

$$V_{c_3} = V_{B_2} = V_{B_1}$$

$$V_{B_1} = \left(\frac{I_t R_{c_1}}{2} - V_{B_3} \right) \frac{R_6}{R_{E_3}}$$

$$V_{B_1} = \left[\frac{I_t R_{c_1}}{2} - V_{B_3} \right] \frac{R_6}{R_{E_3}}$$

$$V_{B_1} = \frac{R_2 V_{cc}}{R_1 + R_2}$$

and

$$I_t \approx \frac{V_{B_1}}{R_5}$$

C_4 , connected between the emitter of Q_3 and ground, is a decoupling capacitor to prevent high-frequency ripple from appearing at the output and increases the open-loop gain of Q_3 .

The configuration set forth in the drawing is described using NPN-transistors and positive pulses. For a negative pulse follow-hold, one would merely substitute PNP-transistors.

What is claimed is:

1. A follow-hold circuit comprising:

input means adapted to receive an input pulse having width and amplitude;

electronic follower means coupled to said input means and having an output when enabled, for producing an output pulse having the same amplitude as the input pulse, at said output, including a differential feedback video amplifier having a plurality of transistors, two of which have a like terminal coupled in common;

holding means coupled to said follower means and said output and being operative to electrically hold said output pulse at said amplitude for a period of time, comprising a capacitor which is charged to the input pulse amplitude; and

gating means coupled to said follower means and said holding means for electrically controlling the width of the output pulse, including a transistorized switch and a gating signal input coupled to said transistorized switch, wherein said transistorized switch is coupled to said holding means and said like terminals coupled in common such that when a gating signal pulse is applied to said gating signal input said transistorized switch will be enabled, which will enable said differential amplifier and discharge said holding means capacitor, and when said transistorized switch is not enabled said differential amplifier will be disabled and said holding means will hold said output pulse at said same amplitude.
